UNITED STATES PATENT OFFICE

130,158

DESIGN FOR A COMBINATION UNIFORM DRESS

Norman A. Shane, Evansville, Ind.

Application May 24, 1941, Serial No. 101,120

Term of patent 14 years

To all whom it may concern:

Be it known that I, Norman A. Shane, a citizen of the United States, residing at Evansville, in the county of Vanderburg and State of Indiana, have invented a new, original, and ornamental Design for a Combination Uniform Dress, of which the following is a specification, reference being had to the accompanying drawings, forming part thereof.

Fig. 2 is a rear view of the combination uniform dress shown in Fig. 1.

Fig. 3 is a front view of the dress portion of the combination uniform dress shown in Fig. 1, in open position.

Fig. 4 is a front view of the reversible apron panel of the combination uniform dress shown in Fig. 1; and

Fig. 5 is a rear view thereof.

I claim:

The ornamental design for a combination uniform dress, as shown.

NORMAN A. SHANE.
